(57) **CLAIM**

The ornamental design for an electronic fixture, as shown and described.

DESCRIPTION

FIG. 1 is a front elevation view of an electronic fixture showing my new design;

FIG. 2 is a rear elevation view thereof; and,

FIG. 3 is a side perspective view thereof.

The electronic fixture houses electronic components, and is typically attached to a ceiling or wall. Components may be inserted through the larger opening on the rear surface of the electronic fixture. The two smaller openings on each side of the larger opening facilitate the attachment of the fixture to external components or to a ceiling or wall.

The broken line portions shown in FIGS. 2 and 3 illustrate portions of the electronic fixture that form no part of the claimed design.
